[57] CLAIM

The ornamental design for a sequined eyeglass case, as shown and described.

DESCRIPTION

FIG. 1 is a left side elevational view of a sequined eyeglass case showing my new invention, the right side elevational view being a mirror image thereof;

FIG. 2 is a front elevational view thereof;

FIG. 3 is a bottom plan view, the top plan view being a mirror image thereof; and,

FIG. 4 is a rear elevational view thereof.
